(57) **CLAIM**

The ornamental design for a coffee pod holder, as shown and described.

DESCRIPTION

FIG. 1 is a front perspective view of a first embodiment of a coffee pod holder, showing my new design, shown in an open condition;

FIG. 2 is a front perspective view of the coffee pod holder of FIG. 1, shown in a closed condition;

FIG. 3 is a front elevational view thereof;

FIG. 4 is a left side elevational view thereof, with the opposite side being a mirror image thereto;

FIG. 5 is a back elevational view thereof;

FIG. 6 is a top plan view thereof;

FIG. 7 is a bottom plan view thereof;

FIG. 8 is a front perspective view of a second embodiment of a coffee pod holder showing my new design, shown in an open condition;

FIG. 9 is a front elevational view thereof shown in a closed condition;

FIG. 10 is a left side elevational view thereof, with the opposite side being a mirror image thereto;

FIG. 11 is a back elevational view thereof;

FIG. 12 is a top plan view thereof; and,

FIG. 13 is a bottom plan view of thereof.
